Elexir J. Key of Lowell, Mass.

Assignor to

The Lowell Manufacturing Company of the same place.

Letters Patent No. 2003-Dated Nov 15-1864.

Design for a Carpet Pattern.

The schedule referred to in these letters Patent and making part of the same.

To all whom it may concern:

Be it known that Elexir J. Key of Lowell in the County of Middlesex and State of Massachusetts have originated and designed a new Pattern for Carpets or other fabrics of which the following is a full, clear and exact description, reference being had to the accompanying drawings, making part of the same.

A is a centre composed of two small blocks and surrounded by scroll B.

C and D when matched will form a centre and scroll similar to A and B.

E, F, G, H are halves of an irregular shaped set figure resting on the centre I, J, K, L which is composed of blocks and in form similar to A, B, C, D.

M and N are either resting between centres C and D and surrounded by piping work.

O is a mottled ground surrounded by key work P.

Note.

This specification refers to that part of drawings between the two blue lines.

The colors employed for the different portions of the design, may be varied at the taste and wish of the manufacturer.

Claim.

What I claim as my invention and desire to secure by Letters Patent is the Design or Pattern for carpets or other fabrics herein set forth.
